UNITED STATES PATENT OFFICE.

ROBERT E. WILSON, OF CHICAGO, ILLINOIS, ASSIGNOR TO STANDARD OIL COMPANY, OF WHITING, INDIANA, AND CHICAGO, ILLINOIS, A CORPORATION OF INDIANA.

LIQUID AND MECHANICAL SEAL.

Application filed March 24, 1924. Serial No. 701,610.

The present invention relates to improvements in sealing devices and more particularly to such devices employed in connection with vent pipes from storage tanks containing volatile liquids such as gasoline, petroleum and the like. It will be fully understood from the following description, illustrated by the accompanying drawing, in which a form of construction embodying the invention is shown in vertical section in the single figure of the drawing.

As shown in the drawing, the device is formed as a substantially upright casing 5, preferably substantially cylindrical in form and having near its lower end an upwardly directed pipe-connecting portion 6 to which the vent pipe from a storage tank may be connected. An annular bottom member 7 closes in an annular compartment 8 formed by a cylindrical member 9 which projects upwardly from the bottom member 7. The cylindrical member 9, which, as hereinafter pointed out, functions in part as a guide member, extends above a transverse annular partition 10, which divides the annular compartment 8 from a similar upper annular compartment 11. A shorter cylindrical guide member 12 extends from the bottom of the device 7 upwardly within the cylindrical guide 9 and spaced a sufficient distance therefrom to permit the free movement of the sealing cap 13, which is provided with a skirt 14 extending into the space between the guides 9 and 12. A short distance above the plane of the annular partition 10 a transverse bar 15 is secured to the guide cylinder 9, this transverse bar serving as an upper limit to the movement of the cap 13.

Above the transverse partition 10 and outside of the cylindrical guide 9 is provided a guide member consisting of six substantially equally placed vertical strips 16, 16 extending from the partition 10 to the top of the casing where their ends are bent outwardly and then down a short distance on the outside of the casing 5. These six strips 16, 16 are spaced a slight distance from the cylindrical guide member 9 to permit the free movement therebetween of the cap 17, which has a skirt 18 freely movable between the guide 9 and the guide strips 16 in the same manner as the cap 13 operates between the guides 9 and 12.

A transverse bar 19 having its ends at-

tached to the upper horizontal portions of two diametrically opposite strips 16 extends across the top of the casing to serve as a limit for the upward movement of the cap 17.

The cylindrical guide member 9 is provided with large openings 22 below the plane of the partition 10, said openings extending substantially from said partition 10 to the bottom 7 of the casing. 23 indicates the openings between the vertical members 16, 16 which openings it will be noted extend to the partition 10.

A suitable protecting cover 25 is supported by the casing on the three supporting members 26 which have their lower ends bent outwardly and then downwardly to engage the upper edge of the casing 5 to hold said cover 25 in place.

The guide member 9 above the partition 75 is provided with openings 35 in its upper part and likewise the guide member 12 is provided with openings 36 in its upper part.

In operation, the device is supported so as to permit free passage of air into it from below, and is connected by means of the connecting pipe portion 6 with a conduit or pipe leading from the vent of the storage tank, for example, a gasoline storage tank. A suitable liquid, preferably a non-volatile oil such as mineral seal oil, is placed in the annular compartments 8 and 11, extending somewhat above the lower ends of the openings 22 and 23, respectively, in the two compartments. When, by reason of increasing temperature, pressure is generated in the tank and in the connections with the conduit leading from the tank to the casing, this pressure is communicated through the openings 22 in the cylindrical guide member 9 to the interior of the latter and tends to raise the cap 17, the lower end of which is immersed in liquid. The openings 35, 35 in the guide 9 assist in giving free access of the gas to the cap 17. The cap 17 is fitted loosely enough, however, over the guide 9 so that gas can pass downwardly toward the lower edge of the cap 17 on the inside between its inner surface and the outside of the guide 9. When this cap has been raised sufficiently so that the head of liquid outside of the cap is not sufficient to balance the pressure of gas, gas escapes under the skirt 18 of the cap 17 and bubbles up through the liquid into the compartment 11, thereby re-

lieving the pressure within the system. It is to be noted that the cover 25 is spaced some distance above the top of the casing which is open so that gas thus vented may

5 freely escape from the top of the compartment 11. Under these conditions, the pressure of the gases in the system tends to hold the cap 13 firmly seated on the guide 12.

When, by reason of atmospheric or other causes, there is a diminished pressure in the system, in excess of a predetermined amount, the partial vacuum created tends to pull the cap 17 firmly down on its seat on the upper end of the guide 9. Air then tends 15 to be drawn up through the opening in the bottom of the casing, raising the cap 13 until its lower end is sufficiently raised in the liquid so that the head of liquid outside of it will not balance the air pressure 20 from within whereupon air escapes around the lower edge of said cap 13 bubbling up through the liquid into the compartment 8 thereby relieving the vacuum in the system.

25 The openings 36 in the upper end of the cylindrical member 12 give freer access of entering air to the cap 13. This cap, however, is loosely enough fitted on the guide 12 so that air can pass downwardly between its 30 interior surface and the outer surface of said guide 12.

In the form of construction illustrated, it will be seen that the entire interior of the device is readily accessible from above. The cover 25 may be easily removed by lifting it 35 off. The bar 19 may then be easily removed by detaching its ends from the two strips 16. After removal of the bar 19, the cap 17 may be lifted out by simply sliding it up inside of the guide strips 16 and out at 40 the top. The bar 15 may then be easily removed from the guide member 9 by taking out the cap screws 37, 37 which hold its ends. After the removal of the bar 15 the cap 13 may be lifted out by merely sliding it 45 up inside of the guide 9 and lifting it out at the top of the casing. The device may hence be readily inspected and cleaned. It is to be particularly noted that the guide 50 9 is of a uniform internal diameter throughout its entire length and that the guide strips 16, 16 likewise form a guide member having a uniform diameter which diameter is greater than the internal diameter of the guide member 9. When the cover, and the 55 cross strips 19 and 15 are removed, the cap 17 may easily be lifted out through the top of the casing and then likewise the cap 13.

While I have shown and described certain 60 embodiments of my invention, it is to be understood that it is capable of many modifications. Changes, therefore, in the construction and arrangement may be made without departing from the spirit and scope of the invention as disclosed in the appended claims, in which it is my intention 65

to claim all novelty inherent in my invention as broadly as possible in view of the prior art.

I claim:

1. In a pressure and vacuum relieving seal, 70 a casing with a bottom and having a transverse partition above said bottom, a cylindrical guide member extending from the bottom of the casing upwardly through said partition, a sealing cap slideable within the 75 guide member and opening through the bottom of the casing to the exterior thereof, a second sealing member above the partition and surrounding the cylindrical guide member, said sealing member being open to the 80 space in the casing below the partition, means for making an external pipe connection with the interior of the casing below the partition, and means for retaining a liquid in said casing on its bottom and on 85 said transverse partition.

2. In a pressure and vacuum relieving seal, a casing having a central opening at its bottom, a central transverse partition in said casing provided with a central opening, a 90 guide member surrounding the central opening in the bottom of the casing and extending through the opening in said partition, said guide member being provided with 95 openings below the plane of said partition, a short guide member within the first-mentioned guide member, a sealing cap normally resting upon said shorter guide member and slideable between it and the first-mentioned 100 guide member, a sealing cap normally resting upon the first-mentioned guide member above the central transverse partition, a guide for said cap spaced exteriorly of the said guide member, said exterior guide being provided with openings and guide members 105 forming annular compartments in said casing above and below the transverse partition, a lateral opening into the lower of said compartments for connection to a gas-containing system, the casing being provided 110 with a central opening above the upper cap.

3. In a pressure and vacuum relieving seal; a casing having an opening at the top and the bottom, and having a transverse partition with an opening therethrough; 115 means for making an external pipe connection with the interior of the casing below the partition; means for retaining a liquid in said casing on its bottom and on said transverse partition; an inlet sealing cap below the partition having its interior communicating with the opening in the bottom of the casing to the exterior thereof; a vertical guide for said cap, said guide extending upwardly through said partition, an outlet sealing cap above the partition slideable on said guide and having its interior communicating with the opening in said partition to the space in the casing below said partition; 120 both of said caps being removable through 125

the opening in the top of the casing without disturbing said guide.

4. In a pressure and vacuum relieving seal; a casing having an opening at the top and the bottom, and provided with a transverse partition having an opening therethrough; means for making an external pipe connection with the interior of the casing below said partition; an outlet sealing cap over the opening in the partition having its open end sealed in a body of liquid on said partition; a vertical guide for said cap, said 25 guide extending downwardly through said partition, an inlet sealing cap over the opening in the bottom of the casing slidable on said guide and having its open end sealed in a body of liquid on said bottom; both of said caps being removable through the opening in the top of the casing without disturbing said guide.
5. In a pressure and vacuum relieving

seal; a casing having an opening at the top and the bottom, and provided with a transverse partition having an opening therethrough; means for making an external pipe 25 connection with the interior of the casing below said partition; an outlet sealing cap over the opening in the partition having its open end sealed in a body of liquid on said partition; a vertical guide for said cap, said 30 guide extending downwardly through said partition, an inlet sealing cap over the opening in the bottom of the casing slidable on said guide and having its open end sealed in a body of liquid on said bottom; said guide 35 being open at the top and the opening in the top of the casing being of sufficient size whereby both caps are adapted to be lifted upwardly out of the guide and through the opening in the top of the casing without disturbing said guide. 40

ROBERT E. WILSON.
